(57) **CLAIM**

What is claimed is the ornamental design for a Y-strap leather
grip, as shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a front view showing the Y-strap leather grip of
Applicant's invention.

FIG. 2 is a back view of the Y-strap leather grip of Applicant's
invention.

FIG. 3 is a left side view of the Y-strap leather grip of Appli-
cant's invention, both sides being identical.

FIG. 4 is a right side view of the Y-strap leather grip of
Applicant's invention, both sides of the case being identical.

FIG. 5 is a top view of the Y-strap leather grip of Applicant's
invention; and,

FIG. 6 is a bottom perspective view of the Y-strap leather grip
of Applicant's invention.
